UNITED STATES PATENT OFFICE

2,161,172

PRACTICE GUN

Louis Kassler, New York, N. Y.

Application May 14, 1937, Serial No. 142,530

11 Claims. (Cl. 273—101.2)

This invention relates to non-shooting or dummy guns adapted for use in target practice, and more particularly to that type of device wherein the image of a target is projected on to a screen or wall and wherein means is provided, which operates upon aiming the gun and pulling the trigger to automatically project a spot on to the screen at that point at which the gun is being aimed.

More particularly, the invention relates to a device of this character wherein means is provided, which operates on pulling of the trigger to puncture the target by means of a needle or other sharp instrument and wherein the needle follows the course of movement of the gun in aiming, and on pulling of the trigger, is automatically projected through the target.

A further object of my invention is to provide an improved moving target with suitable figures thereon, such as those of birds in flight.

Other objects of my invention include simplicity of construction; such an economy of manufacture that the device may be sold as a toy; durability in construction; accuracy of functioning; and ease of manipulation.

Further objects and advantages may be seen from the following description taken in connection with the accompanying drawings, which show several embodiments of my invention and wherein:

Figure 1 is a side elevation partly in section of one form of the device;

Figure 2 is a sectional view taken on the line 2—2 of Figure 1, most of the parts being shown in top elevation;

Figure 3 is an enlarged central sectional view partly broken away and partly in elevation showing the detail of the target puncturing mechanism;

Figure 4 is a sectional view also enlarged taken on the line 4—4 of Figure 3;

Figure 5 is a detail perspective view of the gun trigger and its mounting;

Figure 6 is an enlarged sectional view taken on the line 6—6 of Figure 3.

Figure 7 is an enlarged detail sectional view taken on the line 7—7 of Figure 3;

Figure 8 is a view similar to Figure 1, but showing a modification;

Figure 9 is an enlarged central sectional view, partly in elevation, of the structure shown in Figure 8;

Figure 10 is a vertical sectional view taken on the line 10—10 of Figure 8;

Figure 11 is an enlarged detail view of the

trigger actuating switching mechanism shown in Figure 9;

Figure 12 is a view taken from the opposite side of the mechanism shown in Figure 11 and showing the parts in a different position;

Figure 13 is a sectional view taken on the line 13—13;

Figure 14 is a sectional view taken on the line 14—14 of Figure 11;

Figure 15 is an enlarged detail view of certain of the parts shown in Figure 12;

Figure 16 is a side elevation of a moving target construction; and

Figure 17 is an end elevation of the construction shown in Figure 16.

Referring more particularly to Figure 1, reference character 20 denotes a casing whose interior is divided by a partition 21 into a compartment 22 at the left and compartments 23 and 23' at the right, a horizontal partition 21' separating the compartments 23 and 23'. The partition 21 is provided with an opening 25 to display a target 26 or preferably a series of targets printed on a strip 27, which strip is held against the opening 25 by L shaped metal flanges 28 shown more particularly in Figure 4.

The front wall of the casing 20 is provided with a bushing 32 extending therethrough and in which is slidably mounted a tube 33 adapted to hold a lens or lenses 34 for the purpose of projecting the image of the target on a screen 35. The tube 33 may be moved in and out to focus the lens. Mounted on the base of the compartment in a bracket 37 is an incandescent lamp 38, back of which is a reflector 39 placed at approximately an angle of 45° to the bottom of the casing 20.

Secured to the sides of the casing 20 at the rear thereof are opposite channel members 42, between which extends a supporting plate 43, which together with the partition 21, form bearings for a vertical shaft 44. Mounted on the top of the shaft 44 and secured thereto by a bolt and nut 45 is a U shaped member or clip 46, which pivotally supports at 47 near its upper end the dummy gun 48 which comprises a stock 49 and a barrel 50 with sight, trigger 52 and trigger guard 53. The trigger 52 has an upward extension 57 which projects into a chamber 58 hollowed out of the gun stock and is adapted to engage a lever 60 pivoted at its rear end at 61, extending forwardly and provided with an opening 63 near its forward end.

When the trigger is pulled, the lever 60 is raised and the forward end of the lever engages

- a knob or other enlargement 64 at the upper end of a rod or wire 65, thus raising the rod, the effect of which will be more particularly described hereafter.
- 5 Pivotedly mounted on the horizontal partition or floor 21' is a stud 70, formed U shaped at its upper ends, and pivotedly mounted at 71 between the sides of the U is a body member 72 and adapted to move in a vertical plane. The member 72 is formed with a cylindrical compartment 75 therein which communicates with the outside through an upper slot 76. Mounted to slide in the chamber 75 is a plunger 77, having a rearward extension 79 which snugly fits and slides in a bore 80.
- 15 Located in a chamber 75 and surrounding the extension 79 is a helical spring 82 bearing at one end against the shoulder 83 and at its rear end against the rear wall of the chamber 75.
- 20 Secured in the plunger 77 and extending forwardly through the forward end of the body member 72 is a needle 85, the point 86 of which, in the position of the parts shown in Figure 3, extends through the paper or other puncturable target. The body member 72, intermediate at its ends, is formed with an upward extension 88, formed as a U at its top, between the sides of which at 89 is pivoted a lever 90 having a rearward extension 93' and a forward hooked shaped extension 92, the forward end of which latter extension is inclined, as indicated at 93. The lever 90 is normally maintained in the tilted position by a helical spring 94, bearing at one end against the forward portion of the lever 90 and at the opposite end against the bottom of a bore 91 in the body member 72.
- 25 Mounted in the plunger 77 and extending upwardly through the slot 76 is a cylindrical stud 95, the top of which is expanded to form a head 97 in the bottom of which is an annular recess 98, in which in the retracted position of the plunger, the extension 93 of the lever 90 is adapted to be received.
- 30 The rear end 91 of the lever 90 is secured to the rod 65 and the rear end of the body 72 is connected by a rod 98' with the trigger guard 53 of the gun 50. It will be seen that due to this latter connection, during aiming movements of the gun, the pivotal point of engagement of the rod 98' with the body member 72 will partake of the movements of that point of the gun at which the rod 98' is secured. To secure the proper scanning of the target 26 by the needle to correspond to points at which the gun is aimed, the proper proportioning of parts is obviously an essential factor.
- 35 Lying on the partition 21' is a lever 100, preferably of sheet metal, having an opening 101 surrounding the shaft 44, and the metal of the lever is bent up at 102 to form an ear which is bolted to the shaft 44 at 104. The forward end of the lever carries a stud 105, which is adapted to be received in an elongated opening 106 in a bar 107 rigidly secured to the stud 70.
- 40 It will be seen from the above construction that the turning force is applied to the shaft 44 at two points, one at the connection of the clip member with the shaft 44 and the other at the connection of lever 100 with the shaft, the movement of the gun being transmitted to the shaft through the connecting rod 98', body 72, stud 70 and bars 107 and 100.
- 45 The body member 72 is formed with two laterally extending brackets 110, having openings therethrough in which is adapted to slide a bar
- 50 111, formed at one end with an offset portion 112 adapted to engage the stud 95 for the purpose of moving the stud and plunger against the action of the spring 82 to retracted position, moving the point of the needle away from the target 5 26. Rod 111 may, if desired, be provided at its rear end with a handle (not shown) for retracting the rod in order to insure the rod remaining in its forward position, that is, in a position in which the extension 112 is out of contact with the stud 95. A helical spring 114 is employed, which surrounds the rod and bears at its rear end against one of the two brackets 110, and at its forward end against a collar 112 suitably secured to the rod 111. 15
- 55 From the above description, the operation will be clear. Considering the parts in the positions shown in Figure 1 with the target inserted between the flanges 30, the operator adjusts the tube 33 so that the proper image of the target 20 is thrown on the screen 45. He then pulls the rod 111, and the plunger 77 and the stud 95 are retracted, by engagement with the offset portion 112 on the rod 111, until the expanded top 97 engages the forward inclined end of the extension 25 92 of the lever, thence turning the lever in a counterclockwise direction and permitting the hooked forward end of the lever to enter the annular recess 98. In this position, the plunger and needle are held in retracted position with the 30 point of the needle adjacent to and in back of the target.
- 60 The gun is then aimed and all vertical and horizontal movements of the gun are imparted to the body member 72 through the connection 35 98. As the image of the target is thrown on the screen is reversed, it will be seen from the construction shown that upward movements of the gun muzzle will be converted into a downward movement of the needle, and likewise movement 40 of the gun muzzle to the left, will result in movement of the needle 85 to the right.
- 65 When the gun has been aimed, the trigger is pulled and the extension 57 on the trigger raises the lever 60, which in turn raises the rod 65, 45 45 tilting the lever 90 in a counterclockwise direction and releasing the hooked end 93 from the stud 97, thus permitting the spring 82 to force the plunger 77 and needle 85 to a position where the point of the needle has punctured a hole in 50 the target. The parts are then in a position shown in Figure 3. The rod or bar 111 is then pulled, withdrawing the needle from the target and returning the parts to position shown in Figure 1 with the needle locked in retracted position. Light from the lamp 35, instead of being reflected from the entire target surface toward the lens, will pass through the opening made by the needle, and there will thus be a dark spot formed on the image of the target on the screen 60 35, indicating the point at which the gun was aimed.
- 70 In the construction shown in Figure 1, the needle is manually withdrawn after the trigger is pulled. In the construction shown in Figures 8 65 to 15, the needle is automatically withdrawn and means is provided for controlling the movement of the needle electrically.
- 75 In the latter construction, the mounting of the gun on the clip 46, shaft 44 and bearings for the shaft are substantially the same as that shown in Figures 1 to 4. As may be seen in Figure 9, the rotary stud 70' carries a supporting member 120, which is pivotally connected at its rear end 75

to a bar 121 riveted at 122 to a downwardly extending projection 123 of the trigger guard 53.

The metal support 120 carries at its forward end an electromagnet or solenoid 125 having a core or armature 126. The solenoid is preferably iron clad, and the core has a rear enlargement 128 of soft iron, between which and the rear of the coil is an electric spring 130 which tends to move the armature to retracted position. Secured to and extended forwardly of the armature and out through the forward end of the coil 125 is a needle 132, which is shown in Figure 9 in its retracted position and a short distance behind the target. The trigger 52' is designed to operate a switch shown conventionally in Figure 9 and shown in detail in Figures 11 to 15. Figure 12 shows conventionally the electric circuit through the solenoid 125.

The stock 49' of the gun shown in Figure 9 is formed with a recess, compartment or chamber 58, and mounted on a side wall of said chamber is a supporting plate 140 formed with an upper projecting stud 144 and a lower stud 145.

Pivotedly mounted on the stud 144 is a plate 147 formed with a large central opening 148, beneath which is a projecting lug 149. The metal of the plate 147 is cut away at 150, the cut away metal being bent at approximately right angles to the surface of the plate forming a trigger 52'.

Pivotedly mounted on the stud 145 and extending upwardly therefrom is a plate 152, the upper part of which is bent at right angles to the lower part at 153 and formed as an extending lug 154, the purpose of which will be described hereafter.

Mounted on the portion 153 is a laterally extending movable contact 156 which is adapted to engage a stationary contact 157 mounted on a fibre plate 158, held by suitable rivets 159 to extensions 160 and 161 of the stationary plate 140. The metal of the extension 161 of the plate 140 is bent forward at 163 to form a stop for the forward swinging movement of the plate 147, and the metal of the plate 140 is cut away and bent forward at 164 to form a stopwise for the plate 147.

Likewise mounted on the stud 145 of the plate 140 is a downwardly extending dog or pawl 165, having an upper extension 166 adapted to engage a stud 167 secured to the pivoted plate 152. A relatively weak spring 164 connects the extension 166 with the lug 154 on the plate 152 and a relatively strong spring 170 connects the portion 153 with a stationary lug 171 on the plate 140.

The stationary plate 140 may be grounded, as at 173, and the stationary contact 157 is connected by a conductor 174 with a suitable source of supply 175, which in the present instance may be a pair of dry cells, to one terminal of the source of supply 175 and the other terminal may be connected to one terminal of the coil 125, the other terminal being grounded as at 176.

The operation of the device shown in Figures 8 to 15 is as follows:—

When the gun is aimed and the trigger pulled, the plate 147 is swung toward the left, as shown in Figure 12 against the action of the spring 170 and during this movement, the weaker spring 164 maintains the extension 166 in contact with the pin 167 on the pivotal plate 152. During this movement, the stud 149 approaches and engages the lower end of the pawl 165 (see, for example, Fig. 11). Further movement of the trigger toward the left in Figure 12 brings the pawl and stud into the position shown in Figure 11, and also brings the movable contact 156 into engagement with the stationary contact 157, thus clos-

ing the circuit through the source of supply and the coil 125. When this occurs, the coil attracts the armature 126 against the action of the spring 130, causing the needle 85 to advance and penetrate the target. Upon further movement toward the left of the trigger in Figure 12, the parts assume a position in which the pawl 165 has left the stud 149, thus permitting the relatively strong spring 170 to turn the plate 152 in a counterclockwise direction, disengaging the contact 156 from the contact 157, thus breaking the circuit. When this occurs, the spring 130 of the coil 125 retracts the needle 85 to a position shown in Figure 9.

During the operation thus far described, extension 166 of the pawl 165 remains in contact with the lug 167. On the return movement of the trigger (toward the right in Fig. 11), which takes place under the action of the spring 170, the stud 149 swings the pawl 165 in a counterclockwise direction as viewed in Figure 12, and at this time, the extension 166 leaves the stud 167, thus stretching the weaker spring 164 and permitting the stud 149 to pass under the pawl 165 until the parts regain their initial position, as shown in Figure 12. It will be seen that during this return movement, the contacts 156 and 157 are not reengaged. The spot thus formed on the target is projected on the target image, thus indicating the accuracy of the marksman's aim.

Figures 16 and 17 show a modified form of target 30 get wherein a target disk 180 has depicted thereon, such as that shown at 181, indicating a bird in flight. The target disk is mounted to rotate a central bearing member or stud 183, which is suitably supported from the partition 21' by an L shaped bracket 186. In practice the target disk will be spun before aiming and the needle which penetrates the disk will serve to stop this rotation, thus giving a persistent indication on the screen of the accuracy of the aim. 40

I claim:

1. In a device of the character described, a markable target, means for illuminating the front face of said target and projecting light therefrom forwardly of the gun to form an inverted image of the same, a gun, a pivotal support therefor, a marker behind said target, a pivotal support for said marker, an operating connection between said gun and support whereby aiming movements of the gun barrel are communicated to said mark. 45

2. In a device of the character described, a markable target, means for illuminating the front face of said target and projecting light therefrom forwardly of the gun to form an inverted image of the same, a gun, a pivotal support therefor, a marker behind said target, a pivotal support for said marker, an operating connection between said gun and support whereby aiming movements of the gun barrel are communicated to said marker, the connection with the barrel and marker passing through one pivoted support. 55

3. In a device of the character described, a markable target, means for illuminating the front face of said target and projecting light therefrom forwardly of the gun to form an inverted image of the same, a pivoted gun, a needle behind the target, a pivotal support for said needle, resilient means adapted to retract said needle, electromagnetic means adapted to overcome said resilient means to advance said needle to puncture the target and means controlled by the gun trigger for momentarily closing and opening a circuit through said electromagnetic 70 75

- means when the trigger is pulled and maintaining said circuit open during return of said trigger.
4. In a device of the character described, a markable target, means for illuminating the front of said target and projecting an image thereof on a screen in the front of the gun, a movably supported gun having a trigger, a marker behind said target, an operating connection between said gun and marker for positioning said marker to mark said target at a point corresponding to the point of the image at which the gun is aimed, means between trigger and marker whereby on pulling said trigger said marker is advanced to said target and means for withdrawing said marker from said target.
5. In a device of the character described, a markable target, means for illuminating the front of said target and projecting an image thereof on a screen in the front of the gun, a movably supported gun having a trigger, a marker behind said target, an operating connection between said gun and marker for positioning said marker to mark said target at a point corresponding to the point of the image at which the gun is aimed, means between trigger and marker whereby on pulling said trigger said marker is advanced to said target, and manual operated means for withdrawing said marker from said target.
6. In a device of the character described, a markable target, a projecting apparatus adapted to form an image of said target, a pivoted gun having a trigger, a needle adjacent said target, resilient means adapted to retract said needle, an electromagnet adapted to overcome said resilient means, a source of current, opposing switch contacts, a mechanical connection between said trigger and contacts whereby on pulling the trigger, the contacts are momentarily closed during a small fraction of the pulling motion of the trigger and opened and are maintained open throughout the return motion of the trigger.
7. In a device of the character described, a markable target, a projecting apparatus adapted to form an image of said target, a pivoted gun having a trigger, a needle adjacent said target, resilient means adapted to retract said needle, an electromagnet adapted to overcome said resilient means, a source of current, opposing switch contacts in the gun, a mechanical connection between said trigger and contacts whereby on pulling the trigger, the contacts are momentarily closed during a small fraction of the pulling motion of the trigger and opened and are maintained open throughout the return motion of the trigger.
8. In a device of the character described, a markable target, a pivoted gun having a trigger, a support, a casing universally pivoted on said support and adjacent a face of said target, a marker movably mounted in said casing, a spring tending to move said marker toward said target, a catch engaging said marker for holding said marker in retracted position, a rod extending from said gun to said catch for releasing said catch, a connection between said trigger and rod for moving said rod, a second rod extending from said gun to said casing for communicating movement of said gun to said casing.
9. In a device of the character described, a markable target, a pivoted gun having a trigger, a support, a casing universally pivoted on said support and adjacent a face of said target, a marker movably mounted in said casing, a spring tending to move said marker toward said target, a catch engaging said marker for holding said marker in retracted position, a rod extending from said gun to said catch for releasing said catch, a connection between said trigger and rod for moving said rod, a second rod extending from said gun to said casing for communicating movement of said gun to said casing and manually operated means for retracting said marker.
10. In a device of the character described, a markable target, a pivoted gun having a trigger, a support, a casing universally pivoted on said support and adjacent the face of the target, a pointed rod forming a marker movably mounted on said casing, a spring tending to move said rod towards said target, said rod being formed with a head and a catch for engaging said head for holding said rod in retracted position, a member extending from said gun to said catch for releasing said catch, a connection between said trigger and member for moving said member, and a second member extending from said gun to said casing for communicating movement of said gun to said casing.
11. In a device of the character described, a markable target, a pivoted gun having a trigger, a support, a casing universally pivoted on said support and adjacent the face of the target, a pointed rod forming a marker movably mounted on said casing, a spring tending to move said rod towards said target, said rod being formed with a head and a catch engaging said head for holding said rod in retracted position, a rod extending from said gun to said catch for releasing said catch, a connection between said trigger and rod for moving said rod, and a second rod extending from said gun to said casing for communicating movement of said gun to said casing.

LOUIS KASSLER.
